(57) **CLAIM**

The ornamental design for a table and stool set, as shown and described.

DESCRIPTION

FIG. 1 is a front perspective view of the stool and table set.

FIG. 2 is a Front elevation view thereof (the front elevation view being a mirror image for rear, left and right views).

FIG. 3 is an Offset elevation view thereof.

FIG. 4 is a Top plan view thereof.

FIG. 5 is a Perspective view of the table of the table and stool set.

FIG. 6 is a Front elevation view thereof (the front elevation view being a mirror image for rear, left and right views).

FIG. 7 is an Offset elevation view thereof.

FIG. 8 is a Top plan view thereof.

FIG. 9 is a Perspective view of a stool of the table and stool set.

FIG. 10 is a Rear elevation of the stool.

FIG. 11 is a Front elevation view of the stool as in FIG. 10.

FIG. 12 is a Top plan view thereof.

FIG. 13 is a Right side elevation view of the stool (the left side elevation view being a mirror image thereof.); and,

FIG. 14 is a bottom view thereof.

The slotted handles shown in phantom lines in the rear of the stool and elements shown in phantom lines on the front of the stool are shown for environmental purposes only, and form no part of the claimed design.
